US0D1063655S

(12) **United States Design Patent** (10) **Patent No.:** **US D1,063,655 S**
Wang et al. (45) **Date of Patent:** **** Feb. 25, 2025**

(54) **VEHICLE DIAGNOSTIC TESTING APPARATUS**

(71) Applicant: **Autel Intelligent Technology Corp., Ltd., Shenzhen (CN)**

(72) Inventors: **Yongshuai Wang**, Guangdong (CN); **Yuelong Liao**, Guangdong (CN)

(73) Assignee: **Autel Intelligent Technology Corp., Ltd., Shenzhen (CN)**

(**) Term: **15 Years**

(21) Appl. No.: **29/812,713**

(22) Filed: **Oct. 24, 2021**

(30) **Foreign Application Priority Data**

May 18, 2021 (CN) 202130297384.9

(51) **LOC (15) Cl.** **10-05**

(52) **U.S. Cl.**

USPC **D10/75**

(58) **Field of Classification Search**

USPC D10/46, 65, 75, 103

CPC G01M 17/00

(57) **CLAIM**

The ornamental design for a vehicle diagnostic testing apparatus as shown and described.

DESCRIPTION

FIG. 1 is a front perspective view of a vehicle diagnostic testing apparatus showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the encircled portion 9 of FIG. 1

FIG. 10 is an enlarged view of the encircled portion 10 of FIG. 2; and,

FIG. 11 is an enlarged view of the encircled portion 11 of FIG. 2.

The broken lines depict portions of the vehicle diagnostic testing apparatus in which the design is embodied that form no part of the claimed design.

1 Claim, 11 Drawing Sheets
